J. LUNDSTROM

HOLDER FOR PLUMB RULES

Filed April 26, 1924

Fig. 1

Fig. 2

Fig. 4

Fig. 3

The diagram illustrates a cross-sectional view of a device assembly. At the top, a circular component with a central vertical rod is shown. The rod is labeled with the number 16 at the top and 14 near its base. A circular feature on the rod is labeled 15. To the right of this circular component, a rectangular base is depicted, labeled with the number 11. The base has two rectangular cutouts, one on the left labeled 19a and one on the right labeled 17. A central circular feature on the base is labeled 20a. The base is supported by a structure labeled 18, which is further supported by a base labeled 21.

Inventor:
John Lundstrom
By: John, Joachim Jr.

UNITED STATES PATENT OFFICE.

JOHN LUNDSTROM, OF EVANSTON, ILLINOIS.

HOLDER FOR PLUMB RULES.

Application filed April 26, 1924. Serial No. 709,108.

To all whom it may concern:

Be it known that I, JOHN LUNDSTROM, a citizen of the United States, residing at Evanston, in the county of Cook and State of Illinois, have invented certain new and useful Improvements in Holders for Plumb Rules, of which the following is a specification.

Considerable difficulty and inconvenience has been experienced by brick masons in that the plumb rule necessary in their work, when not in use, is generally laid upon a wall, scaffold or like place, with the result that they are often knocked off and injured or broken, and at other times they are so placed that bricks are dumped or thrown upon or against them.

It is one of the objects of the present invention to provide an improved holder for holding the plumb rule when not in use and consists essentially in a receptacle or holder adapted to be readily attached to a mortar or other board and as readily detached or removed therefrom, and which receptacle or holder itself will not only be out of the way of the user but will be adapted for receiving and holding other tools or implements.

A further object is to provide an improved device of this character which will be of a simple, durable, and comparatively compact construction.

To the attainment of these ends and the accomplishment of other new and useful objects as will appear, the invention consists in the features of novelty in substantially the construction, combination and arrangement of the several parts hereinafter more fully described and claimed and shown in the accompanying drawing illustrating this invention, and in which—

Figure 1 is an end elevation of an improved device of this character constructed in accordance with the principles of this invention.

Figure 2 is a view partly in side elevation, partly broken away and partly in section.

Figure 3 is a horizontal sectional view taken on line 3—3, Figure 1.

Figure 4 is a sectional view taken on line 4—4, Figure 1.

Figure 5 is a detail view partly in section, showing a modified means for fastening the parts together.

Referring more particularly to the drawing the numeral 10 designates generally a

bracket having an arm or member 11 adapted to project beneath a mortar or like board 12. The bracket is also provided with a portion 13 projecting over the member 11 and is spaced thereabove a suitable distance to permit the insertion of the end of a suitable board or support. Carried by the member 11 is a screw 14 to which is swiveled a head 15 and is provided with an operating handle 16 so that when the bracket is placed over the edge of the board 12, the screw 14 may be adjusted in the member 13 for clamping the bracket upon the board. Carried by the bracket is a laterally projecting portion 17 having up-standing walls 18 and corners, and the member 17 is preferably provided with openings 19 therethrough, for a purpose to be hereinafter set forth. If desired a suitable re-inforcing or strengthening rib or web 20 may be provided.

The inner faces of the walls 18 are preferably provided with recesses 21, any number of which may be provided, and these recesses are preferably spaced above the base 17.

A receptacle 22 preferably constructed of sheet material is shaped into the desired configuration and is tubular, both ends thereof being open, the upper end being preferably rolled as at 23 while the extremity of the lower end of the tubular member 22 is preferably flanged inwardly as at 22^a for re-inforcing purposes and is adapted to be inserted within the walls 18 of the base 17 so as to rest upon the base. The walls of the receptacle 22 are preferably provided with outwardly projecting portions 24 so located that when the end of the tubular member 22 is inserted within the walls 18 and the extremity of the tubular member 22 engages and rests upon the base 17, the lugs or projections 24 on the walls of the receptacle will enter the recesses 21 in the walls 18 for securing the parts together.

Obviously these parts may be secured together in any other desired or suitable manner and any number of these lugs or projections 24 with the corresponding recesses 21 may be provided. If desired screws 21^a may be used as a fastening means.

The receptacle thus formed may be of any desired size and height but is preferably of a length to receive and hold a plumb rule.

The openings 19 in the bottom or base 17 are provided to permit the passage therethrough of any foreign matter such as mortar, pieces of stone or brick, or the like 5 which might fall into the receptacle 22.

If desired a false or removable bottom 25 may be placed within the receptacle to cover the openings 19, and thereby adapting the receptacle to receive and hold 10 smaller tools or implements.

If desired an encompassing band 26 may be provided around the receptacle 22 at any desired point throughout the length thereof. This band 26 may be of any suitable 15 material and may be held in position in any desired or suitable manner but preferably by providing recesses 27 in the element 26, which are adapted to receive projections on the walls of the receptacle 22.

20 Obviously the projections and recesses on the receptacle 22 and the element 26 as well as the lugs and recesses 21-24 may be reversed.

A portion of the encompassing member 26 is preferably deflected as at 29 so as 25 to stand away from the adjacent portion of the wall of the receptacle 22. A supplemental receptacle 30 of any desired size and configuration may be provided with a hook shaped suspending portion 31 30 adapted to engage over the deflected portion 29 of the member 26 to pass between this deflected portion and the adjacent wall of the receptacle 22 for removably or detachably suspending the receptacle 30.

35 This receptacle 30 is adapted to be used when it is desired to suspend or hold other tools or implements in a convenient position for use.

Additional supporting means 32 such as 40 an annular element or the like may also be secured to the outer surface of the receptacle 22, such as by means of fastening bolts or screws 33 or in any other manner to hold the element 32 rigidly projected with respect 45 to the wall of the receptacle 22.

Any number of these elements 32 may be provided about the walls of the receptacle 22 and are adapted to receive and hold an implement such as a brick mason's hammer 50 or the like.

With this improved construction it will be manifest that the receptacle may be readily attached to the mortar or any other suitable board or support and when in position 55 the operator may place the plumb rule or any of his implements or working tools within the various holders provided therefor. At the same time the receptacle 22 will be out of the way of the operator and 60 may be readily detached from the board

when desired and can be transported with the tools therein and stored away in a convenient manner for use the next day.

If desired the receptacle 22 may be provided with a suitable lining 22^b for protecting the plumb rule and a cushion or bumper 19^a of any suitable material may be provided on the bottom 19 and against which cushion the end of the plumb rule strikes when the latter is dropped into the 70 receptacle.

While the preferred form of the invention has been herein shown and described it is to be understood that various changes may be made in the details of construction 75 and in the combination and arrangement of the several parts, within the scope of the claims, without departing from the spirit of this invention.

What is claimed as new is:-

1. A holder for a plumb rule and the like embodying a clamp, a portion of the clamp being shaped to form a base and upstanding walls, a tubular element open at both ends, one of the ends of the tubular element being disposed within the said walls and supported by the said base, and interlocking means between the walls of the tubular member and the said upstanding walls. 80

2. A holder for plumb rules and the like embodying a base, an open receptacle projecting into the base, means securing the receptacle and base together, means connected with the receptacle adjacent the base 85 for detachably securing the same to a board or support, there being comparatively large openings through the base for the passage of foreign particles therethrough, and a removable bottom within the receptacle for closing the said openings. 95

3. A holder for plumb rules and the like embodying an open elongated receptacle, a clamp connected with the receptacle for removably securing the receptacle to a support, a band encompassing the receptacle intermediate its ends, portions of the upper edge of the band being deflected to form an opening between the receptacle wall and the deflected portion of the band, an additional receptacle, and a hook shaped portion on said additional receptacle adapted to engage over the edge of the deflected portion of the band and project between the band and the adjacent wall of the receptacle. 105

In testimony whereof I have signed my name to this specification, on this 19th day of April, A. D. 1924.

JNO. LUNDSTROM.
